(57) **CLAIM**

The ornamental design for a wearable mobile electronic device, as shown and described.

DESCRIPTION

FIG. 1 is a top, front, and left side perspective view of a wearable mobile electronic device of the present invention; FIG. 2 is a top, front, and right side perspective view thereof; FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a bottom, front, and right side perspective view thereof; and,

FIG. 10 is a bottom, front, and left side perspective view thereof.

The broken lines of the Figures illustrate portions of the wearable mobile electronic device that form no part of the claimed design.

1 Claim, 10 Drawing Sheets
